Letters Patent No. 2298. Dated, May 1, 1866.

Design for a Trade Mark.

The schedule referred to in these Letters Patent is making part of the same.

To all whom it may concern:

Be it known to all, that Franklin O. Day and Wm. L. Abbott, of the City, and County of St. Louis, and State of Missouri, had invented a new design for Trade Mark, the same being a Brand for Whisky Barrels; and we do hereby declare that the following is a full and clear description thereof, reference being had to the accompanying drawings which fully illustrate the nature of this invention. The head of the barrel is fitted and painted in the following manner: The ends or heads of the staves and a annular band concentric with the said band being seven inches wide are colored and painted red, or some near approach to that color. Immediately on the said colored band, and commencing at the top of the lettering, are capital letters forming the word "superior," which word is formed in a segmental line concentric with the colored band, above mentioned. Immediately below the word "superior" are the words "rectified Whisky," also in capital letters and disposed in a curve line, the center of which is curved upward towards the center of the word "superior," and the enlarged space which is thus formed below the center of the words "rectified Whisky" is filled with the word "from," in an elliptical line, bounded by ornamental lines, immediately over which is a space between it and the words "rectified Whisky" are placed the letters "L" and "P" in a segmental line. Below the word

In and nearly in the center of the barrel head, and receding across this same in a straight line are the words, Derby and Day, in large capitals and below this again also in a straight line, the words and figures lettered as follows, viz: 422, Water Street, and below these again the words St. Louis, Mo., in capital letters. All of the above lettering is done with a black color. In the center of the barrel head there is a large star painted in a silver color of red, and enclosing a small star of white, the natural color of the wood of the head of the barrel. The field on which the above letters and figures are painted is made of the same lumber and of red, is the natural color of the wood forming the head of the barrel.

Spec. in the design for a Trade Mark, composed and arranged substantially as shown and described.
